[57] CLAIM

The ornamental design for a motor vehicle bumper guard, substantially as shown and described.

DESCRIPTION

FIG. 1 is a perspective view of a motor vehicle bumper guard showing my new design, with a typical bumper shown in broken lines for illustrative purposes only;
FIG. 2 is a top plan view thereof;
FIG. 3 is a front elevation view thereof;
FIG. 4 is a bottom plan view thereof; and
FIG. 5 is a side elevation view thereof.
